UNITED STATES PATENT OFFICE.

ADOLPH SCHWANKE, OF WENONA, ILLINOIS.

ENVELOPE-MOISTENING AND STAMP-AFFIXING MACHINE.

Application filed April 25, 1921. Serial No. 464,141.

To all whom it may concern:

Be it known that I, ADOLPH SCHWANKE, a citizen of the United States, a resident of Wenona, in the county of Marshall and 5 State of Illinois, have invented new and useful Improvements in an Envelope-Moistening and Stamp-Affixing Machine, of which the following is a specification.

This invention has reference to a new and 10 improved envelope moistening and stamp affixing machine.

One of the objects of the present invention is to provide a simple, inexpensive, and practical machine of the character referred 15 to especially adapted for desk use.

The invention has for a further object to provide an envelope moistening and stamp affixing machine adapted to be used first for moistening the flap of the envelope that it 20 may be sealed and then for moistening the corner of the envelope and affixing a stamp thereto. The movement of the envelope during the moistening and stamp affixing is adapted to actuate means which will feed a 25 stamp strip and permit the affixing of the stamp to the envelope and the detachment of such affixed stamp from the strip of stamps.

A further object of the invention is to 30 provide the machine with a stamp strip feeding and stamp severing means adapted to be simultaneously actuated as the corner of the envelope is moistened and moved to position for the affixing of a stamp thereto.

That the invention may be more fully 35 understood, reference is had to the accompanying drawings forming a part of the description and illustrating a preferred embodiment of the invention in which:

Fig. 1 is a side elevation of an envelope 40 moistener and stamp affixing machine embodying my improvements, the stamp strip feeding means being in its normal position;

Fig. 2 is a view of the machine similar to Fig. 1, with the exception that the means 45 for feeding the stamp strip has been actuated and is in the position it would assume during the affixing of a stamp to an envelope;

Fig. 3 is a plan view of the machine as it 50 is shown in Fig. 2, with the exception that a part of the base of the machine is broken away;

Fig. 4 is a vertical longitudinal sectional 55 view through the machine, the parts being shown in the position they are in in Fig. 1;

Fig. 5 is a vertical longitudinal sectional view through the machine, the parts being shown in the position they are in in Fig. 2;

Fig. 6 is a perspective view in plan on the line indicated by the arrows in Fig. 5, showing the stamp strip feeding plate and the means for preventing backward movement of the stamp strip when the actuating means returns to its normal position, and

Fig. 7 is a detail cross section in plan as 65 the same would appear if taken on the line 7-7 of Fig. 4.

In the drawings, 1 designates an elongated base supporting a table 2, the latter at a suitable point formed or provided with a transverse slot 3 to receive a cutter to be herein-after referred to. At one end of the table there is secured in an upstanding position a stamp strip container 4 which supports a cup 5 to receive a sponge or similar article 6. 70 The stamp strip container has journaled therein a spindle 7 on which is reeled a stamp strip 8. Said spindle, as will be understood, is removable so as to receive the reeled stamp strip, in the manner shown in 75 the drawings. To the upper front face of the container and just below the cup 5 is secured a buffer 9, the use of which is to be further described.

Slidably supported on the table 2 is a 80 stamp strip feeding plate 10 formed or provided with string clip gripping fingers 11, adapted when the plate 10 is moved in one direction to engage with the stamp strip 8 and feed said stamp strip forward the distance of the length of one stamp. Said 85 plate is formed with a centrally disposed elongated slot 12. Extending longitudinally of the plate 10 and secured thereto are ribs 13, the forward ends of which have journaled therein the transverse rod or spindle 14 which for a portion of its length is carried within a sleeve 15.

16 designates arms which are pivotally connected on either side of the table 2 by 100 means of a pivot pin 17; such arms normally assuming an upstanding position immediately in front of the stamp strip container and the sponge holder as is clearly seen in the drawings. Connecting the said arms 16 and disposed longitudinally therebetween from a suitable point removed from their upper ends is a spring plate 18 provided with a guard 19 and formed at its upper end with a cutter 20'. Said spring plate at a 105 110

suitable point removed from the plate 10 is bent forwardly under a transversely disposed sleeve 20 and the forward end of said spring plate overlies and has a bearing upon the sleeve 15. The sleeve 20 is carried by a rod or spindle 21 connected with the two said arms 16 and also connected with the said rod or spindle 21 are reach members 22 which at their opposite ends are connected with the rod or spindle 14.

When the arms 16 are returned to their normal upstanding position by means of the spring plate 18, the guard 19 engages with the buffer 9 and it being preferably made of rubber or some such material, relieves the jar and deadens the noise of impact.

Beneath the table 2 is secured a spring clip 23 projecting up through an opening 24 in the table and said spring clip functions to prevent the return of the stamp strip 8 with the rearward movement of the plate 10 in the event of any frictional relation between said plate and said stamp strip. As will be understood the spring clips 11 on the plate 10 move the stamp strip forwardly and the spring clip 23 holds the stamp strip against any backward movement. The opening 12 in the plate 10 removes the danger of any frictional contact between the spring clip 23, the stamp strip 8, and the plate 10, leaving the spring clip 23 free to act as a retarding member only for the stamp strip 8. It will be understood that when the arms 16 are moved forwardly and downwardly oscillating the same upon the pivot pin 17 that such movement will fold the spring plate 18 into the position shown in Fig. 5, and that when the arms are released the spring plate automatically unfolds, returning the plates 16 to their normal upstanding positions seen in Fig. 4.

By reason of the fact that the rod or spindle 21 is connected with the arms 16, as said arms are moved forwardly and downwardly the reach members 22 will be reciprocated forwardly and through their connection with the rod or spindle 14, will move the feeding plate forwardly also, and as the spring clips 11 engage the stamp strip 8, they will move it forwardly and across the slot 3 in the bed. This movement of the stamp strip is sufficient to carry the same forward beyond the slot 3 the distance of one stamp as seen in Fig. 5, and simultaneously the cutter 20' severs the stamp from the stamp strip and enters the slot 3 in the bed as shown, the edges of said slot serving as complementary cutting means to the cutter 20'.

In the operation of the device the flap of an envelope may be moistened by drawing the gummed portion of the flap across the moistened sponge 6 and then sealing the flap down. To affix a stamp to the corner of an envelope, the envelope is grasped in

the hand with the corner to which the stamp is to be affixed facing downwardly. The corner of the envelope is then drawn across the sponge 6 to moisten the surface of the envelope, and this movement is continued forwardly and downwardly which will move the arms 16 in like direction, moving said arms and parts associated or connected therewith from the position shown in Figs. 1 and 4 to the position shown in Figs. 2, 3 and 5. Such movement, through the connection of the reach bars 22 with the plate 10 will feed the stamp strip 8 forwardly placing the end stamp of the strip just beyond or forward of the slot 3 in the table 2, in which position the moistened corner of the envelope will be brought into engagement with said end stamp, and pressure of the hand, while at the same time moving the envelope forwardly along the table will force the knife 20' into the slot 3 severing the end stamp from the strip 8 leaving it attached to the envelope. The extension 19 of the spring plate 18 provides the means by which the person affixing the stamp may press the knife 20 down into the slot 3 to sever the stamp. Also such extension 19, when the arms 16 are returned to their normal position, contacts with the buffer member 9 deadening the noise of impact. From the foregoing, it is obvious that the envelope corner is moistened, the stamp strip fed forwardly, the stamp affixed, and the stamp severed all with one motion of the hand, that of a forward and downward movement, and that when the arms 16 are released the spring plate 18 returns the arms 16 to their upstanding position and the plate 10 to feeding position, and the spring clip 23 prevents backward movement of the stamp strip.

What I claim is:—

1. In a stamp affixing machine, in combination, a base, a table provided with a slot, a container at one end of said table, means to revolvably hold a reeled stamp strip in said container, a sponge holder on said container, a stamp strip feeding means on said table, means pivoted to the table and normally disposed in front of said container, operating connections between said pivoted means and said feeding means, a knife on said pivoted means adapted to enter the slot in the table, means to return the pivoted means and feeding means to normal position, and means to prevent backward movement of the stamp strip.

2. In a stamp affixing machine, in combination, a table, means to rotatably hold a stamp strip for movement longitudinally of said table, a feeding plate overlying and spaced from said table and slidable thereon and provided with means to engage and feed the stamp strip forwardly, operating means pivotally connected with said table,

operating connections between said operating means and said feeding plate, a cutter associated with said operating means, means to return the operating means and feeding 5 means to normal position, and means to prevent backward movement of the stamp strip.

3. In a stamp affixing machine, in combination, a table, means to rotatably hold a stamp strip for movement longitudinally of 10 said table, a sponge holder, a plate slidable on said table and provided with stamp strip feeding means, operating means for said plate including arms pivotally connected with said table, reach bars connecting said 15 arms with said plate, a spring plate connecting said arms and adapted to fold during the feeding movement of said plate and to unfold and return said arms and plate to normal position upon the release of said 20 arms, and means on the table to prevent backward movement of said stamp strip.

4. In a stamp affixing machine, in combination, a base, a table having a transverse slot, a stamp strip container at one end of said table, a sponge holder supported by 25 said container, a plate movable on and longitudinally of said table, stamp strip engaging means on said plate, arms pivoted on either side of said table and normally assuming an upstanding position in front of said container, bars connecting said arms and said plate, means connecting the arms adapted to return said arms and plate to normal position after each feeding operation, a knife to sever the individual stamps from the 30 strip after each feeding operation, a buffer to receive the impact of said arms, and means on the table to prevent backward movement of said stamp strip.

In witness whereof, I have hereunto affixed my hand this 19th day of April, 1921.

ADOLPH SCHWANKE.
